UNITED STATES PATENT OFFICE.

EDWIN A. OLLEY, OF SYRACUSE, NEW YORK, ASSIGNOR TO CROUSE-HINDS COMPANY
OF SYRACUSE, NEW YORK, A CORPORATION OF NEW YORK.

PANEL-BOARD CONSTRUCTION.

1,303,582.

Specification of Letters Patent. Patented May 13, 1919.

Application filed August 2, 1915. Serial No. 43,121.

To all whom it may concern:

Be it known that I, EDWIN A. OLLEY, a citizen of the United States, residing at Syracuse, in the county of Onondaga and 5 State of New York, have invented a certain new and useful Panel-Board Construction, of which the following is a specification.

This invention has for its object a panel board construction, and particularly the production of an electrical appliance by which the load circuit controlling devices as the 10 switches and the fuse connections are so arranged that the widthwise dimension of the panel board is materially reduced; and the 15 invention consists in the combinations and constructions hereinafter set forth and claimed.

In describing this invention, reference is had to the accompanying drawings, in which 20 like characters designate corresponding parts in all the views.

Figure 1 is a plan view of a panel board embodying my invention.

Fig. 2 is an enlarged section on the plane 25 of line A—A, Fig. 1.

Fig. 3 is an elevation, partly in section, looking to the right in Fig. 2, parts being omitted.

Fig. 4 is a plan view of the inner base of 30 the appliance, the switch mechanism being removed.

My electrical appliance for panel boards comprises, generally, supporting means and circuit controlling devices carried by the 35 supporting means and connected in series, said devices being preferably arranged one above the other. The supporting means in this form of my invention comprises two insulating bases as inner and outer units, one 40 extending above and inclosing the other, and switch and fuse devices mounted respectively on the units.

More specifically this appliance comprises, a base, a switch mounted on the base 45 and including terminals, a switch arm movable into and out of position to close and open the circuit across the terminals, and operating means for the switch arm, and a second base rising above the first base and 50 supporting an electrical receptacle, as a fuse receptacle, having terminals connected in series with the former terminals, the operating means for the switch arm being exposed through the second base, and the second base preferably having a skirt inclosing 55

or housing the switch mechanism and also the first base.

1 is the panel or base of the panelboard, 2, 3 are the bus bars, and 4, 5, are the load circuit bar sections connected, respectively, 60 to the bus bars 2, 3. 6, 7 are respectively, load circuit bar sections paired with the sections 4, 5, and having their inner ends offset from the panel 1, as at 8, and opposed to the inner ends of the sections 4, 5, which 65 are offset at 8^a.

9 designates one of the bases of the electrical appliance which is mounted on the panel 1 over the bar sections 4, 5, 6, 7 and has barriers 10, 11 separating said sections 70 and resting on the upper face of the panel 1.

12, 13 are pairs of terminals of the switch, the terminal 12 of each pair being connected to the offset end 8 of the corresponding bar section of the load circuit bar sections, as 75 the bar section 6 or 7 by screws 12^a. Each terminal 12 is here shown as consisting of a base 14 secured by a screw 15 to the base 9, and an upwardly extending flange 16 having projecting from one edge thereof, a 80 switch contact 17. The screws 15 extend into the base 9 from the underside thereof; and the screws 12^a serve to electrically connect the terminals 12 and the bars 6, 7.

Each terminal 13 consists of an upright 85 having a foot 19 at its lower end secured to the base 9 by a screw 20 extending into the base and the foot from the lower rear side of the base, the upright having a laterally extending switch contact 21 between its ends 90 and a laterally extending arm 22 at its upper end which terminates in an arc-shaped portion 23 located over the space between the switch contacts. It will be understood that there are two of each of the terminals 12 95 and 13.

25 are switch arms which move about an axis, the opposite ends of the arms 25 moving into and out of engagement with each pair of contacts 17 and 21. As there are 100 two pairs of contacts 17, 21, there are two switch arms 25. The switch here shown is of the push button type, and as the mechanism of this type of switches is well known, further description is thought to be unnecessary. 105

The operating means or push buttons of the switch mechanism are designated 27, 28 and extend upwardly through openings in the top of the second base to be described. 105

29 designates the second base which includes a top superposed above the switch mechanism, and a skirt or housing 30 inclosing the switch mechanism, and also inclosing the base 9 and resting at its lower edge on the panel 1, the skirt having cutouts 37 in its lower edge through which the load circuit bar sections 4, 5, 6, 7 pass. The push buttons 27, 28 extend through the top of the base 29.

The electrical receptacles mounted on the top of the base 29 are here shown as adapted to receive fuse plugs and each includes a sleeve terminal 31 located in a suitable socket 15 32 formed integral with the base 29 and a central terminal 33. Each sleeve terminal includes a suitable base flange 34 which is overlaid by a washer 35, and the washer is clamped to hold the sleeve in position by 20 means of a pair of diametrically disposed screws 36 extending through the top of the base 29 and threading into the arc-shaped end portion 23 of one of the terminals 13, hence making electrical and mechanical connection therewith. Each central terminal 25 33 consists of a long screw extending through the body 29 of the base through the space inclosed by the skirt 30, through the base 9 and threading into the offset end 8^a 30 of the bar section 4 or 5. Thus the terminals 31, 33 are connected in series with the switch contacts 17 and 21. The screws 33, 36, in addition to making electrical connection, mechanically secure the base 29 in position. 35

In operation, assuming that the switch is closed and that fuse plugs are inserted in the fuse plug receptacles to connect the terminals 31, 33, the current passes from one bus bar, as 3, through load circuit bar section 5, terminal or screw 33 of one fuse plug receptacle, through the fuse plug to sleeve terminal 31, through the screws 36 to one terminal 13, and switch contact 21 thereof, 40 thence through one switch arm 25 to one terminal 12 and thence through one screw 12^a, load circuit bar section 7, around through the load circuit, to the bar section 6, through the other screw 12^a, terminal 12 45 electrically connected to the bar section 6, the companion switch arm 25, switch contact 21 and terminal 13 on which said contact is provided, through the screws 36, 50 sleeve terminal 31 of the other fuse plug receptacle, through the fuse plug in said receptacle, and thence to the other load circuit bar section 4 and bar 2 by way of the ter- 55

terminal 33 of the last-mentioned fuse plug receptacle.

This electrical appliance is particularly 60 advantageous in that the fuses and switches are so combined that they occupy substantially the same space in a widthwise direction of the panel board, so that the widthwise dimension of the panel can be reduced 65 compared with switch boards heretofore in use in which the switches and the fuse receptacles have been separate units.

What I claim is:—

What I claim is:

1. An electrical appliance for panel boards 70 comprising supporting means, switch and fuse-receiving devices carried by the supporting means, the supporting means comprising a base mountable upon a panel board, the switch device being located within 75 the base and the fuse-receiving device being mounted on the top of said base above the switch and switch operating means extending through the top on the base adjacent the fuse-receiving device whereby the switch 80 and fuse-receiving devices occupy substantially the same area on the base, substantially as and for the purpose described.

2. An electrical appliance for panel boards comprising two units, one being mounted above the other, one unit comprising a base and switch mechanism mounted thereon, and the other unit comprising a base and electrical receptacles mounted thereon, the operating mechanism for the switch extending to the outside of the latter unit, and means for mechanically and electrically connecting the units together, substantially as and for the purpose described. 85 90

3. An electrical appliance for panel boards 95 comprising inner and outer units, the inner unit comprising a base and switch mechanism mounted thereon and having operating means extending to the outside of the outer unit and the outer unit comprising a base 100 and fuse-receiving devices carried on the face thereof, the base having openings through which said operating means extend, and means for electrically connecting the terminals of the fuse receiving devices to the 105 switch terminals and mechanically connecting the bases together, substantially as and for the purpose described.

In testimony whereof, I have hereunto signed my name at Syracuse, in the county of Onondaga, and State of New York, this 30th day of July, 1915.

EDWIN A. OLEARY
